UNITED STATES PATENT OFFICE

164,153

PORTABLE FILM VIEWER OR SIMILAR
ARTICLE

Robert M. Barth, Pelham Manor, N. Y., assignor
to The FR Corporation, New York, N. Y., a cor-
poration of New York

Application March 28, 1951, Serial No. 14,653

Term of patent 14 years

(Cl. D61—1)

To all whom it may concern:

Be it known that I, Robert M. Barth, a citizen of the United States, and a resident of Pelham Manor, Westchester County, New York, have invented a new, original and ornamental Design for a Portable Film Viewer or Similar Article, of which the following is a specification, reference being had to the accompanying drawing, forming a part hereof, in which:

Fig. 1 is a perspective view of a portable film viewer or similar article, showing my new design, in open position, looking from the viewing end thereof;

Figure 2 is a perspective view thereof, in open position, looking from the opposite end of Figure 1;

Figure 3 is a perspective view thereof similar to Figure 1, but in closed position;

Figure 4 is a side view thereof, as seen in Figure 1;

Figure 5 is a plan view thereof, as seen in Figure 3;

Figure 6 is a side view of the device, as seen in Figure 5;

Figure 7 is a bottom view of the device, as seen in Figure 6;

Figure 8 is a left end view, looking in the direction of the arrow 8, of Figure 6;

Figure 9 is a right end view, looking in the direction of the arrow 9, of Figure 6;

Figure 10 is a plan view of the device with the cover removed; and

Figure 11 is a bottom view of the cover, removed from the device.

I claim:

The ornamental design for a portable film viewer or similar article, as shown.

ROBERT M. BARTH.
